UNITED STATES PATENT OFFICE.

JOHN D. RAFERT, OF CLEVELAND, OHIO.

ARM-SUPPORTER.

1,083,338.

Specification of Letters Patent.

Patented Jan. 6, 1914.

Application filed May 1, 1913. Serial No. 764,752.

To all whom it may concern:

Be it known that I, JOHN D. RAFERT, a citizen of the United States of America, residing at Cleveland, in the county of Cuya-

5 hoga and State of Ohio, have invented cer-
tain new and useful Improvements in Arm-
Supporters, of which the following is a
specification, reference being had therein to
the accompanying drawings.

10 This invention relates to an arm supporter
for athletes and more particularly for base
ball players, the device being adapted to re-
lieve the arm from the shock incurred when
a ball is suddenly released in the art of
15 throwing.

The invention consists in the matters here-
inafter set forth and particularly pointed
out in the appended claims.

20 In the drawings, Figure 1 is a view show-
ing a supporter in position; Fig. 2 is a view
of the back of the arm; and Fig. 3 is a view
of the supporter removed from the body of
the user.

25 As herein shown in preferred form, an
adjustable upper arm band 1 that may have
an elastic section therein, if preferred is
connected by inelastic straps 2 with an el-
bow band 3 which may likewise be elastic if
30 desired. A fore arm band 4 is secured by
an extension 5 of the band 3 to the wrist
band. Buckles 6 or like take up means pro-
vide for the adjustment in length of these
inelastic parts.

35 An elastic shoulder band 7 extends from
the point of the wearer's shoulder through a
guide 8 in the upper band 1 and a similar
guide 9 in the elbow band 3 to the fore arm
band 4. The guide 9 is not in alinement
40 with the guide 8 so that the elastic member
7 passes to the inside of the fore arm as indi-
cated in Fig. 1, while the non-elastic con-
nections 2 lie on the top of the fore arm
and front of the upper arm. Other non-
45 elastic connections indicated at 10 connect
the upper bands. The upper end of the
member 7 is secured either to a yoke 11 that
is adapted to be laced into position over the
shoulders and under the arm pits of the

wearer or it may be secured directly to the
uniform or suit of the user.

50

Suitable take up buckles 12 are provided
for adjusting the device to the wearer.

An elastic strip 13 is secured to the elbow
band and the forearm band in such manner
as to pass over the point of the elbow when
55 the arm is flexed, and thereby support the
arm during certain movements thereof.

As a result of this construction, a sup-
porter is obtained which while it moves
readily to the movement of the arm, as in
throwing a ball, reinforces the muscles pass-
ing through the elbow and thereby aids the
55 latter in overcoming the inertia of the arm
when a thrown ball leaves the hand. It
may be adjusted in such manner as to suit
the individual requirement of the wearer
60 and afford an effective means for relieving
the strain upon the arm. Furthermore, the
supporter aids the arm muscles in throwing
the ball, and enables the user to project the
70 ball with greater speed than he can obtain
without its aid.

Obviously, changes in the details of con-
struction may be made without departing
from the spirit of my invention and I do not
75 care to limit myself to any particular form
or arrangement of parts.

What I claim as my invention is:—

1. An arm supporter comprising a band
adapted to be adjustably secured around the
upper arm near the shoulder, a band adapt-
ed to be secured around the upper arm near
the elbow, inelastic, flexible and adjustable
connections between the upper and lower
bands, a fore arm band, an inelastic, adjust-
able and flexible connection between said
band and the band near the elbow, an elastic
connecting member adapted to be secured to
the wearer at the point of the shoulder at
one end and at the other end to the fore-arm
band, in sliding engagement with the other
band.

2. An arm supporter comprising a band
adapted to be adjustably secured around the
upper arm near the shoulder, a band adapt-
ed to be secured around the upper arm near

the elbow, inelastic, flexible and adjustable connections between the upper and lower bands, a fore arm band, an inelastic, adjustable and flexible connection between 5 said band and the band near the elbow, an elastic flexible connection between the elbow band and the wrist band adapted to pass over the point of the elbow of the wearer, and an elastic connecting member adapted 10 to be secured to the wearer at the point of

the shoulder at one end and at the other end to the fore-arm band, in sliding engagement with the other band.

In testimony whereof I affix my signature in presence of two witnesses.

JOHN D. RAFERT.
